UNITED STATES PATENT OFFICE.

CHARLES P. KEMBLE, OF CHICAGO, ILLINOIS, ASSIGNOR TO THE KENNICOTT COMPANY,
OF CHICAGO, ILLINOIS, A CORPORATION OF ILLINOIS.

METAL-FORMING MACHINE.

1,201,740.

Specification of Letters Patent.

Patented Oct. 17, 1916.

Application filed October 1, 1915. Serial No. 53,566.

To all whom it may concern:

Be it known that I, CHARLES P. KEMBLE, a citizen of the United States, residing at Chicago, in the county of Cook and State of Illinois, have invented a new and useful Improvement in Metal-Forming Machines, of which the following is a specification.

My invention relates to improvements in metal-forming machines, and more particularly to a type of machine for rolling a concentric series of corrugations in metal-plates.

The nature and objects of my invention will be more fully understood from the following detailed description, taken in connection with the accompanying drawings.

In these drawings, Figure 1 is a vertical sectional view through a machine constructed in accordance with my invention, taken substantially on the line 1 of Fig. 2, and Fig. 2 is a plan view of the revolving platen or table, the upper stationary platen being removed.

Referring more particularly to the drawings, the numeral 10 designates the base or frame of my machine which, as shown in the drawings, is generally rectangular in form and provided on one side with an aperture 11 through which the drive-shaft passes as will later appear. Supported above the base 10 on columns 12 is an upper stationary platen 13 having in its lower face three concentric grooves 14, 15 and 16. For cooperating with this grooved stationary platen there is provided a rotatable table or platen formed of two concentric members, an outer annulus 17 and an inner disk 18. The annulus 17 is provided with ball-races 19, 20, which lie opposite the grooves 14, 15, of the platen 13, while the inner disk 18 is provided with a ball-race 21 which lies opposite the groove 16. Within the race-ways 19, 20 and 21, there are mounted forming balls 22 which are preferably spaced apart as by spacers 23.

For supporting the annulus 17 and disk 18 and for driving the same, there is provided a rotatable table 24 which is supported upon the base 10 as by a ball-thrust bearing 25 and has gear-teeth 26 cut in its periphery which mesh with a driving-pinion 27 carried by a driving-shaft 28 which passes outward through the aperture 11 in the frame and is operated from any desired source of power. Upon the rotatable table

24 there are mounted five fluid-pressure cylinders arranged in two sets. The outer set of cylinders, designated 29, are four in number and receive four plungers 30 which support the annulus 17. The second set comprises a single cylinder 31 mounted concentrically with the table 24 and receiving a plunger 32 which supports the disk 18. For supplying the pressure fluid to the cylinders 29, conduits 33 are formed in the table 24, the said conduits extending downwardly into a hub or spindle 34 formed integrally with or secured to the table 24. All of the conduits 33 communicate with an annular conduit 35 near the lower end of the stem 34 and through the latter conduit the pressure fluid is supplied by a pipe 36 which enters a packed collar 37 having an annular groove 38 which forms constant connection with the annular conduit 35 through ports opening outward from the latter. The cylinder 31 is supplied with fluid under pressure by a conduit 40 arranged axially of the stem 34 and communicating with an axial supply pipe 41 secured in the end of the conduit by a suitable packing gland.

Surrounding the annulus 17 is a rectangular clamping platen 42 which is supported upon the base 10 by four plungers 43 arranged at its corners and operating in fluid-pressure cylinders 44 which are connected with a source of fluid under pressure by pipes 44¹.

In the operation of my machine the plungers 30, 32 and 42, will be brought to their lower or inoperative position by cutting off the supply of fluid under pressure from the respective cylinders and venting these cylinders. The plate to be corrugated, for example, a plate-metal car end, will be pushed in from the side to rest upon the upper surface of the clamping table 42, which is designed to stand at a somewhat higher level than the forming members 17, 18. The fluid pressure will then be admitted to the cylinders 44, thereby elevating the clamp-table 42 to bring the flat plate into contact with the lower face of the stationary platen 13. The drive-shaft 28 may then be started to rotate the table 24 and with it the annulus 17 and central disk 18. By admitting pressure either through the pipe 36 or the pipe 41, or through both of these, depending upon the gage of metal being pressed, and the

power of the driving means, the plungers 30 or 32 or both of these members will be elevated, whereby the forming balls 22 will come in contact with and will roll upon the 5 lower surface of the plate. Sufficient pressure being exerted by the pressure cylinders 29, 31, the balls as they revolve will work the metal of the plate inwardly by a sort of spinning or rolling action forming concentric 10 corrugations as shown at 45 in Fig. 1 of the drawings. When these corrugations have reached their full depth, the drive-shaft 28 may be stopped and by venting the pressure cylinders 29, 31, the forming balls 15 will be withdrawn free of the lower surface of the plate. The cylinders 44 may then be vented to lower the clamping table 42 and when the corrugations of the plate have become free of the grooves in the platen 13, 20 the plate may be removed by a crane or other apparatus.

While I have shown and described in considerable detail one specific embodiment of my invention, it should be understood that 25 such showing and description is illustrative only and for the purpose of making my invention more clear, and that my invention is not to be regarded as limited to these specific details, except in so far as such limitations are included within the terms of the 30 following claims, in which it is my intention to claim all novelty inherent in my invention, as broadly as is possible in view of the prior art.

35 What I claim as new and desire to secure by Letters Patent is:

1. In a metal-forming machine and, in combination, a platen having an arcuate groove in its operative face, a second platen 40 spaced away from the said face and having a ball race opposed thereto and arranged concentrically with the said groove, a forming ball movable in the said race, means for moving said platens toward one another, and 45 means for moving said platens angularly with relation to one another and about an axis concentric with said groove and race.

2. In a metal-forming machine and, in combination, a platen having a circular 50 groove in its operative face, a second platen spaced away from the said face and having a circular ball-race concentric with and opposed to the said groove, spaced forming balls movable in the said race, means for 55 moving said platens toward one another, and means for rotating said platens with respect

to one another, about an axis concentric with the said groove and race.

3. In a metal-forming machine, a platen having a plurality of concentric grooves in its operative face, a second platen spaced away from the said face and having a plurality of concentric ball-races opposed to the said groove, a forming ball movable in each of the said races, means for moving said 65 platens toward one another, and means for rotating said platens relatively to one another and about an axis concentric with the said grooves and races.

4. In a metal-forming machine, a stationary platen having an arcuate groove in its operative face, an annular clamping platen opposed to the said face and movable toward and away from the same to clamp a plate thereagainst, a forming platen spaced away 75 from the said face and having a ball-race opposed to the said groove, a forming ball movable in the said race, means for moving said forming platen toward and away from said stationary platen, and means for rotating said forming platen about an axis concentric with said groove and race.

5. In a metal forming machine, a platen having a plurality of concentric arcuate grooves in its operative face, a plurality of 85 concentric platens spaced away from the said face and having ball-races opposed to the said grooves, forming balls movable in the said races, independent means for moving each of said concentric platens toward 90 said first-named platen, and means for moving said concentric platens and said first-named platen angularly with relation to one another and about an axis concentric with 95 said grooves and races.

6. In a metal-forming machine, a stationary platen having a plurality of concentric grooves in its operative face, means for clamping a plate against the said face, a second platen comprising a plurality of concentric members spaced away from the said face and having each a ball-race opposed to one of the said grooves, forming balls movable in the said races, independent means for moving each of said concentric platens toward said stationary platen, and means for rotating said concentric platens about an axis concentric with said grooves and races.

CHARLES P. KEMBLE.
